UNITED STATES PATENT OFFICE.

EDWARD H. FOWLER, OF BUFFALO, NEW YORK.

KITCHEN-CABINET.

SPECIFICATION forming part of Letters Patent No. 340,944, dated April 27, 1886.

Application filed May 5, 1885. Serial No. 164,510. (No model.)

To all whom it may concern:

Be it known that I, EDWARD H. FOWLER, of the city of Buffalo, in the county of Erie and State of New York, have invented new and useful Improvements in Kitchen-Cabinets, of which the following is a specification.

The object of this invention is the construction of a kitchen-cabinet which will serve as a convenient receptacle for the various utensils and materials used in the kitchen, and in which each material or utensil can be readily reached when required for use, while the space at disposal is fully utilized, thereby forming a compact and serviceable cabinet, which will at the same time serve the purpose of a kitchen-table.

My invention consists, to these ends, of the improvements which will be hereinafter fully set forth, and pointed out in the claims.

20 In the accompanying drawings, Figure 1 is a perspective view of my improved cabinet. Fig. 2 is a horizontal section of the same. Fig. 3 is a vertical section in line $\alpha\alpha$, Fig. 2. Fig. 4 is a vertical section of a hinge of one of the pivoted cases.

Like letters of reference refer to like parts in the several figures.

A represents the top, and A' the bottom, of the cabinet.

30 a represents the back-board connecting the top A with the bottom A', and a' represents an upright board arranged parallel with the back-board, a, and at a short distance in front of the same, whereby a narrow rear compartment, a'', is formed, which is adapted to receive an extension, B, of the top, an ironing-board, and other large articles or utensils. The extension B is provided with hooks b, which enter loops or eyes b', secured to one 40 end of the top A, and by which the extension is attached to the top when required for use—for instance, when a person wishes to sit down to the cabinet. The extension B is further supported by a sliding bar, b'.

45 C C represent vertical boards or partitions arranged at right angles to the board a', and extending from the latter forwardly to the front of the cabinet. The boards C are arranged at suitable distances from the ends of 50 the cabinet, so as to form spaces outside of said boards and between the top and bottom

plates, A A', in which spaces are arranged pivoted cases D D'. The latter are pivoted to the top and bottom plates, A A', by vertical pivots d in such manner that these cases can be arranged to occupy the corner of the cabinet, as represented in the right-hand portion of Figs. 1 and 2, in which position the outer long side of the case forms the end of the cabinet, while its outer short side forms the end portion of the front of the cabinet, or so that the case can be swung out and its long side be placed in line with the front side of the cabinet, as represented in the left-hand portion of Figs. 1 and 2, in which position the case projects beyond the end of the cabinet. The pivots d are arranged equidistant from the front end of the swinging case and from the inner and outer sides thereof, whereby the total length of the cabinet when the cases are swung out is materially shortened, thereby saving room, and whereby the unoccupied space between the inner side of the swinging case and the board C when the case is swung back is reduced to a minimum. The outer long side 75 of the case D is provided with drawers e, for the reception of spices, and the rear portion of the case is occupied by a flour-box, f, which is made open at the top, and which is closed by the top plate, A, when the case 80 D is swung under the same, while it is open when the case is swung out. The outer long side of the case D' is provided with drawers g, for the reception of various meals, and the upper rear portion of the case D' is occupied by sugar-boxes h, which are open at the top, and which are closed by the top A when the case is swung under the same, and open when the case is swung out. The lower rear portion of the case D' is provided with a 85 receptacle, i, for vinegar, &c., which opens outwardly, like the drawers g. The drawers in the pivoted cases D D' open outwardly, and are accessible when the cases are swung back under the top plate as well as when the cases 90 are swung out and placed in line with the front of the cabinet, while the receptacles in the cases which open outwardly are only accessible when the cases are swung out.

j represents a receptacle for a chopping bowl, 100 and k a receptacle for a rolling-pin, secured to the inner long side of the case D.

l represents doors hinged to the front ends of the upright partitions *C*, and closing the spaces between the inner sides of the cases *D* *D'* and the partitions, so as to give access to these spaces when required.

m m represent similar doors hinged to the back board, *a*, and closing the ends of the rear compartment, *a²*, and the spaces between the said compartment and the rear ends of the cases *D D'*.

The central front portion, *N*, of the cabinet between the partitions *C* is occupied by a number of drawers and utensils, which may be arranged in a variety of ways.

15 As shown in the drawings, *n* represents the bread-board; *o*, the meat-board; *p*, the kitchen-tray; *q*, a drawer for miscellaneous utensils; *r*, the scouring-box; *s*, the cabbage-cutter; *t*, the knife-sharpener; *u*, the potato-cutter; *v*, the spoon-tray; *w*, the kneading-board; *w'*, the butler's-tray; *w²*, a drawer for towels, and *w³* drawers for tins, &c.

When all the receptacles are required for use, the cases *D D'* are swung out, whereby 25 their drawers are placed in line with the front of the cabinet, and the flour and sugar boxes are uncovered. In this position of the cases all of the drawers of the cabinet are in line and easily accessible.

30 When the drawers of the pivoted cases are not used, the cases are swung back in place, and the cabinet then occupies no more room than an ordinary kitchen-table and answers all purposes of a kitchen-table, while it affords 35 in a very small space convenient storage for

all the various materials and utensils used in a kitchen.

I am aware that desks have been provided with swinging or pivoted cases containing drawers or other receptacles, and I do not 40 broadly claim such construction.

I claim as my invention—

1. In a kitchen-cabinet, the combination, with a stationary central portion provided at its front with suitable drawers, of a pivoted 45 end case having drawers on its outside, the pivots of the case being arranged equidistant from the front end and the outer and inner sides of the swinging case, substantially as set forth.

2. In a kitchen-cabinet, the combination, with the central portion, *N*, having its front provided with suitable drawers, of the pivoted 50 end cases, *D D'*, and hinged doors *l*, closing the spaces between the central portion and the cases and giving access to said spaces, substantially as set forth.

3. In a kitchen-cabinet, the combination, with the central portion, *N*, and rear compartment, *a²*, of the pivoted end cases, *D D'*, and 60 hinged doors *m*, closing the ends of the rear compartment and the spaces between the rear compartment and the cases, substantially as set forth.

Witness my hand this 15th day of April, 55
1885.

EDWARD H. FOWLER.

Witnesses:

JNO. J. BONNER,
C. F. GEYER.

It is hereby certified that in Letters Patent No. 340,944, granted April 27, 1886, upon the application of Edward H. Fowler, of Buffalo, New York, for an improvement in "Kitchen Cabinets," an error appears in the printed specification requiring correction as follows: In line 98, page 1, the word "outwardly" should read *upwardly*; and that the Letters Patent should be read with this correction therein that the same may conform to the record of the case in the Patent Office.

Signed, countersigned, and sealed this 4th day of May, A. D. 1886.

[SEAL.]

H. L. MULDROW,
Acting Secretary of the Interior.

Countersigned:

M. V. MONTGOMERY,
Commissioner of Patents.
